UNITED STATES PATENT OFFICE

GEORGE C. McCORMICK, OF NEEDHAM, MASSACHUSETTS, ASSIGNOR TO GENERAL ALLOYS COMPANY, OF BOSTON, MASSACHUSETTS, A CORPORATION OF MASSACHUSETTS

CONVEYER FOR HEAT TREATING FURNACES

Application filed September 10, 1930. Serial No. 480,857.

My invention relates to a means for conveying metallic members such as sheets, bars, rods and the like through a furnace for heat treatment.

One object of the invention is to provide an improved conveying means of the roller type which is adapted to convey metal sheets, bars and the like through a furnace in substantially their normal flat condition, the ends of said sheets or bars passing from roll to roll without getting down between said rolls when they sag.

Another object is to provide a supporting means beneath the rolls within the furnace to prevent said rolls from sagging at their centers when subjected to high temperatures.

Another object is to provide rolls with replaceable discs, any one of which may be replaced if worn or damaged.

Another object is to provide an arrangement by which the discs can be strung on the shafts (in the sense that beads are strung) and the discs be so related to the shafts as to turn therewith when the shafts are driven.

With the foregoing objects in view my invention will be best understood from the illustrated embodiment thereof shown in the accompanying drawing, in which

Figure 1 is an elevation of one form of conveyor constructed according to and embodying my invention, parts being shown in section;

Fig. 2 is a sectional view taken on the line 2—2 of Fig. 1, and

Fig. 3 is a detail view of a portion of a tubular shaft with part in section and part in elevation.

By my invention I provide a plurality of tubular shafts having discs mounted thereon in spaced relation. The said discs are so spaced on each shaft so as to stagger the discs on adjacent shafts, thereby making it impossible for a member passing over same to get between the rollers. Anti-friction rollers, mounted in brackets beneath the discs engage one or more of the center discs on two adjacent shafts and support same within the furnace, thereby assur-

ing alignment of the shafts and preventing them from sagging when hot.

The rollers are designated generally by the reference character 10 and comprise preferably tubular shafts 12, the ends of which pass through suitable clearance openings 14 in the walls of a furnace 16 and are supported in end bearings 18 outside of the furnace.

Each shaft 12 has end portions 19 and an enlarged centrally disposed portion 20 with keyways 22 formed therein. The depth of keyways 22 is substantially equal to the enlargement of shaft parts 20 over shaft parts 19 so that the bottom or seat of the keyways form substantially a continuation of the surface walls of shaft portions 19.

A plurality of discs 24 are mounted on the enlarged portion 20 of the shafts 12 each disc comprising a webbed body structure 26 having an outer rim 28, a central opening 30 and keys 32 preferably cast integrally therewith and adapted to engage the keyways 22 in the said enlarged portion 20.

To assemble the discs 24, a collar 34 is first placed over the enlarged portion 20 of shaft 12 and pinned to the shaft by means of a pin 36, then several discs 24 with sleeves 38 therebetween are slipped over the said enlarged portion. After the desired amount of discs have been mounted, another collar 34^a is placed over the enlarged portion 20 of shaft 12 and against the last disc, and is then pinned to the shaft by means of pin 36^a. The discs are therefore held rigidly in place.

On each adjacent roller assembly the discs 34 are mounted in staggered relation, so that discs on alternate shafts intermesh as indicated in Fig. 2.

The clearance openings 14 in the furnace walls are preferably made large enough to permit the enlarged portion 20 of the shaft 12 to pass through when assembling the discs or when replacement is to be made. To prevent the hot furnace gases from escaping a suitable packing 40 of heat resisting material is preferably inserted in the said openings 14.

In conveyors of the roller type there is a

tendency for the rolls to sag at the center when carrying heavy loads while being subjected to high temperatures. To prevent this I have provided a means of support beneath each roller at the center thereof which comprises anti-friction rollers 42 having pintles 44 supported in slotted bearings 46 located in brackets 47 in the hearth of the furnace. The rollers 42 are placed so 5 their centers are in alignment with the intersecting points where the discs overlap thereby placing each roller in a position to engage discs on two adjacent shafts as shown in Figs. 1 and 2.

10 Any suitable driving means may be employed, such as gearing 48 or any other means which will impart uniform rotation to each of the rollers.

Having described my invention I claim:

20 1. A conveyer adapted for use in a heat treating furnace comprising a plurality of shafts journaled at the ends thereof outside of the furnace and having spaced discs thereon, the discs of one shaft being staggered relative to and overlapping the discs of the adjacent shaft, and an idling roller mounted within the furnace below and intermediate of the shafts and adapted to engage certain of the discs of both of the adjacent 25 shafts to prevent the sagging thereof.

30 2. A conveyer adapted for use in a heat treating furnace comprising a plurality of shafts journaled at the ends thereof and having series of discs thereon, the discs of one shaft being staggered relative to the discs of the adjacent shaft, and an idling roller journaled within said furnace below and intermediate of said shafts centrally 35 thereof and adapted to engage the center discs of both of the adjacent shafts to prevent the sagging thereof.

40 3. A conveyer adapted for use in a heat treating furnace comprising a plurality of journaled shafts having spaced discs thereon, the discs of one shaft being staggered relative to and overlapping the discs of an adjacent shaft, and an idling roller supported below said shafts and engaging the center discs of both of the contiguous shafts to 45 prevent the sagging thereof.

50 4. A conveyer adapted for use in a heat treating furnace comprising outer and intermediate rotatable shafts having spaced discs thereon, the discs of the intermediate shaft 55 being staggered relative to and overlapping the discs of the outer shafts, and idling rollers supported below and engaging overlapping discs of the several shafts contiguous to the points of intersection of the peripheries of the discs to prevent sagging of the shafts.

60 5. A conveyer adapted for use in a heat treating furnace, a tubular shaft including a relatively enlarged central portion having 65 longitudinally extending keyways therein

extending from end to end of said enlarged portion, discs provided with hub openings adapted to fit the enlarged central portion and having inwardly projecting keys adapted to interengage the keyways, and means for retaining said discs secured in spaced apart relation on said enlarged portion.

In testimony whereof, I have signed my name hereto.
